Filed Oct. 8, 1958, Ser. No. 766,079

3 Claims. (Cl. 333—98)

The present invention relates to waveguide apparatus employed in propagation of electromagnetic wave energy at microwave frequencies and more particularly to an improved resonant window assembly for switching devices utilizing a gaseous discharge.

Prior art resonant window assemblies having an integral gaseous atmosphere contained within an encapsulated dielectric structure are described in U.S. Patent 2,791,720 issued May 7, 1957 to F. A. Lesch and 2,407,069 issued September 3, 1946 to M. D. Fiske. The advantage of such structures is that the gaseous atmosphere characteristics may be optimized for the arc loss and recovery time electrical parameters when the resonant window assembly is combined with waveguide structure to form a switching device. As a result of the encapsulated window structure improvement in recovery time has been achieved by the use of an electron capture gas such as water vapor in combination with conventional noble gaseous atmospheres. The addition of the water vapor, however, presents certain disadvantages in that oxidation of any exposed metallic surfaces is likely to occur and temperature extremes will result in drastic changes in the water vapor pressure thereby altering the gaseous atmosphere composition. Furthermore, water vapor will freeze at 0° C. which prevents usage of such an additive for switching radar signals at lower operating temperatures.

An analysis of the gaseous discharge phenomena and in particular the deionization processes which determine the recovery time mechanism is necessary to appreciate the improvement disclosed in the present invention. In the conventional gaseous discharge switching of microwave frequency energy, the intense ionization during the transmission cycle results in an electron density in the range of 10^{10} to 10^{13} electrons/cc. dependent upon the incident power, gas composition, gas pressure and configuration of the gas container. The ionization is achieved by the increasing voltage gradient which results in rapid acceleration of electrons to provide elastic collisions and eventually inelastic collisions. Upon cessation of the transmitter energy, the recovery or deionization process must proceed by operation of three processes; namely attachment, recombination and diffusion.

In the switching tube art the attachment mechanism is the most prominently relied upon to control recovery time. In this mechanism, the molecule attaches an electron to form a negative ion. Since water vapor has a high electron affinity it is universally employed as an additive. The fast deionization time achieved, however, has resulted in an increase in the arc loss or thermal energy dissipated within the gaseous discharge container. In many cases this thermal energy is sufficiently high to melt a dielectric material. It has been observed in the art, however, that with a pure dry noble gas such as argon, krypton or xenon the arc loss can be reduced by a factor of 10 to 1. The recovery time, however, would increase beyond the tolerable limits for radar usage since the deionization mechanism now relied upon is a simple diffu-

2

sion process. Inasmuch as the prior art container designs resulted in a relatively long diffusion path, the longer recovery times may be explained. It, therefore, is desirable to employ a pure noble gaseous atmosphere in a container configuration which provides a short diffusion path to result in a low arc loss and a short recovery time in switching electromagnetic energy.

The present invention has for its primary object the provision of a resonant window assembly for gaseous discharge switching devices, said resonant window assembly having improved electric characteristics of low arc loss and short recovery time.

A further object is the provision of an improved enclosure for a gaseous atmosphere for switching of high power electromagnetic energy.

A still further object is the provision of an improved enclosure for containing a gaseous discharge within a relatively small cross-sectional area approximating the mean free path of the gas molecule.

A feature of the present invention resides in the spacing within a gaseous atmosphere container being approximately equal to the mean free path of a selected pure noble gas contained therein. In accordance with the text "Basic Data of Plasma Physics" by Sanborn C. Brown, Technology Press and John Wiley and Sons, Inc., New York 1958 pages 1-18, 48-49 the diffusion length or gap dimension is defined by:

$$\text{Eq. (1)} \quad \Lambda^2 = D\tau$$

30 wherein

D =diffusion coefficient, of gas, and
 τ =recovery time;

hence, by transposing:

$$\text{Eq. (2)} \quad \tau = \frac{\Lambda^2}{D}$$

For parallel plate geometry the diffusion length is defined by:

$$\text{Eq. (3)} \quad \Lambda^2 = \frac{L^2}{\pi^2}$$

wherein L is distance of plate separation

Now, by substituting Eq. 3 in Eq. 2 the following equation results:

$$\text{Eq. (4)} \quad \tau = \left(\frac{1}{\pi^2 D} \right) L^2$$

In accordance with the present invention, therefore, as 50 the distance L becomes smaller the recovery time will also become shorter. It is believed that with the short diffusion path the electrons traverse the gap rapidly and are neutralized by the adjacent plates.

The invention further permits the use of pure noble 55 gases, heretofore not used in conventional gaseous discharge tube envelopes because of the long diffusion path which resulted in high recovery time values.

The calculation of the spacing of the plates to define 60 the gas envelope has been experimentally determined to be approximately equal to the mean free path of a selected gas in accordance with the definition in the aforementioned text on pages 2-3:

$$\text{Eq. (5)} \quad l = \frac{1}{p_0} P_c$$

wherein

$$p_0 = \frac{273_p}{T}$$

70 with p being the actual pressure employed and T is the electron temperature during ionization; and P_c is the av-

verage number of collisions that occur when an electron travels 1 cm. at a pressure of 1 mm. at 0° C.

In the practice of the invention, water vapor as an additive gas in the known art to facilitate the attachment mechanism may be eliminated since the main feature of the present disclosure involves the diffusion mechanism in a gas container having a critically short plate separation incorporated therein.

Other objects, features and advantages will be apparent after consideration of the following detailed specification and accompanying drawings, in which:

Fig. 1 is a side elevational view partially broken away;

Fig. 2 is a side elevational view of the inner box member;

Fig. 3 is a view along the line 3—3 in Fig. 2; and

Fig. 4 is an exploded view of the illustrative embodiment showing the method of assembling the components.

Referring to the drawings, the illustrative embodiment 1 comprises plural parallel metallic plate members 2 and 3 spaced apart a distance approximating the mean free path of a gas molecule to define a very narrow gap 4. Each parallel plate member is provided with a centrally located resonant aperture covered by a dielectric window member 5 and 6. To support the parallel plate members in the desired position and control the critical spacing therebetween each plate member is joined to a short length of rectangular waveguide. Hence, plate member 2 will be hermetically sealed to waveguide 7, while plate member 3 is joined at one end to waveguide 8 of larger overall dimensions. Hence waveguide 7 will be positioned to snugly engage the inner walls of waveguide 8 in a telescoping arrangement. A mounting flange 9 secured as shown provides means for connecting the window assembly to adjacent waveguide structure when the assembly is utilized to form any of the switching devices. Waveguide 7 is provided with wall structure resembling a notch along a narrow side to thereby define with waveguide 8, a passageway 11 for exhausting and introduction of the gas atmosphere.

In the method of assembling the resonant window assembly the outer surface 12 of window 5 should desirably be coextensive with the surface of plate member. It may be necessary, therefore, to grind the dielectric material to achieve the desired flatness. Similarly the excess dielectric material exposed on the inner surface of window 6 must be removed to achieve a flat surface as at 13. With appropriate jigging and measurement fixtures waveguide 7 is inserted within waveguide 8 until gap 4 is defined. The distance "d" between the parallel plate members will approximate the mean free path which by definition is the average distance an electron travels before a collision with a gas atom. Experimental values have been determined from .005 to .050 inch for various noble gases and pressures. For an illustrative example a filling of argon gas at a pressure of 7 millimeters of mercury and a gap spacing of .012 inch resulted in a recovery time of approximately 5 microseconds. The arc loss characteristic was below the sensitivity of conventional measuring techniques.

After insertion of waveguide 7 within waveguide 8 and adjustment of the gap spacing the outer ends of the waveguides may be joined together by fusing of the metal, as at 14 by the process referred to as "Heli-weld" to form a vacuum tight seal. Such a sealing process assures a considerably improved hermetic seal over prior art soldering techniques. A feature of the present window assembly resides in the fact that the intense arc utilized in the welding process is removed from the dielectric window area thereby averting any melting or cracking.

The assembly is evacuated and filled with a gaseous atmosphere by means of tubulation 15 supported by a triangular metallic member 16. Tubulation 15 communicates with passageway 11 to provide access to the gap between the parallel plate members. Other structure for exhausting and filling will be readily apparent and may

be positioned so as to extend within the open area 17 defined by waveguide 7. It will also be possible to provide a gas reservoir within the area 17 by means of a suitable dielectric member in a manner well-known in the art.

After fabrication of the resonant window assembly, any desirable switching device may be formed by attachment of the assembly to suitable waveguide structure with the requisite inductive and capacitive elements 10 commonly found in the art. The window assembly is simply secured to the necessary waveguide structure by soldering or other mechanical means. The window assembly may also be easily replaced whenever necessary without the costly replacement of the entire switching tube. Among the various devices made possible by this arrangement are: transmit-receive; anti-transmit-receive; pre-transmit-receive and attenuator tubes.

The illustrative embodiment has been described with reference to a rectangular structure, however, circular 20 waveguide configurations may be adapted similarly.

What is claimed is:

1. A resonant window assembly for electromagnetic wave energy gaseous discharge switching devices comprising plural spaced parallel plate members having resonant 25 apertures enclosed by material previous to electromagnetic energy, waveguide means secured to each of said plate members with one waveguide being inserted within another to thereby retain the spacing between said plates, said waveguide means being hermetically sealed together to define a vacuum tight enclosure, a filling of a pure noble gas within said enclosure at reduced pressures, the spacing between said plate members being critically short to equal the mean free path of a gas molecule of the selected gas.
2. A resonant window assembly for electromagnetic wave energy gaseous discharge switching devices comprising plural narrowly spaced parallel plate members defining therebetween a gap of critically short dimensions equal to the mean free path of a gas molecule of a gas, 30 each of said plate members having a centrally located resonant aperture with a dielectric window positioned therein, the spacing between said plate members being retained by means of mounting said plate members at the ends of hollow waveguide sections with one of said sections positioned within the other in telescoping arrangement, the opposite ends of said waveguide sections being hermetically sealed together to form a vacuum tight enclosure, and a filling of a pure noble gas under reduced pressure contained within said enclosure.
3. A resonant window assembly for mounting in electromagnetic waveguide structure comprising plural narrowly spaced parallel plate members defining therebetween a gap of critically short dimensions, each of said plate members having a centrally located rectangular aperture with a dielectric window positioned therein, a section of hollow rectangular waveguide secured to each plate member with one of said sections being positioned within the other in telescoping arrangement, the outer ends of said waveguide sections being hermetically sealed together to form a vacuum tight enclosure, a gas selected from the pure noble gases contained within said enclosure under reduced pressure, the dimensions of said gap being equal to the mean free path of a gas molecule of the selected gas.
